AIR SUPPLY DEVICE

Franz J. Kurth and Friedrich Honerkamp, New York, N. Y., assignors to Anemostat Corporation of America, a corporation of Delaware

Application October 27, 1936, Serial No. 107,762

5 Claims. (Cl. 98—39)

Our invention relates to the art of air conditioning rooms or other enclosures, and has particular reference to improvements in devices of the type which are designed to be mounted in an opening in a wall of a room or other enclosure as, for example, an opening in a window pane, for supplying outside air to the room or enclosure.

Generally speaking, the object of the invention is to provide a device of the character referred to which is of comparatively simple construction and of relatively low production and installation cost; which may easily be assembled, disassembled, installed and removed; which combines small size with large air supply capacity; which includes means for practically draftlessly delivering large volumes of air into a room or other enclosure; which may readily and easily be adjusted to entirely cut off the air supply and to regulate the volume of air delivered between a minimum and a maximum without varying the speed of the fan and motor comprising part of the device; and which is thoroughly reliable and highly efficient in operation.

25 Further, and to the end of providing for obtaining exceptionally large air supply capacity in a device of comparatively small size, the invention has in view to provide a fan of novel, highly efficient construction.

30 With the foregoing and other objects in view, which will become more fully apparent as the nature of the invention is better understood, the same consists in the novel features of construction, combination and arrangement of parts as 35 will be hereinafter more fully described, illustrated in the accompanying drawings and defined in the appended claims.

In the accompanying drawings:

Figure 1 is a central, longitudinal section 40 through an air supply and distributing device constructed in accordance with one practical embodiment of the invention.

Figure 2 is a transverse section on the line 2—2 of Fig. 1.

45 Figures 3 and 4 are views similar to Fig. 1 illustrating alternative embodiments of the invention; and

Figure 5 is a side elevation, illustrating an alternative fan construction.

50 Referring to the drawings in detail, first with particular reference to Figs. 1 and 2, it will be observed that the present device comprises a hollow casing, designated generally as A, and that said casing is composed of separate, inner and 55 outer sections, designated as 1 and 2, respectively,

which are separably connected together at their adjacent ends as, for example, by means of screw threads designated as 3.

The sections 1 and 2 preferably are of circular cross section and either or both of the same 5 may be of either cylindrical or tapered form. Preferably, however, the inner section is of slightly outwardly flaring form and the outer section is of somewhat greater outwardly flaring form to provide for free flow of air into the casing and 10 drainage therefrom of any water which may find its way therein.

On the section 1 adjacent to its outer end is an outwardly directed annular flange 4, and on the section 2 at its inner end is an outwardly 15 directed annular flange 5.

At 6 is designated a window pane or other wall element having therein an opening 7 in which is disposed the outer end portion of the section 1, the flanges 4 and 5 being disposed at the inner 20 and the outer sides of said pane or wall element, respectively, as shown, and gaskets 8 and 9 of rubber or other suitable material being interposed between said flanges and said pane or wall element, whereby, when the section 2 is screwed 25 inwardly upon the section 1, the portion of the window pane or wall element 6 surrounding the opening 7 is clamped between the flanges 4 and 5 and the casing A thereby is securely mounted on the pane or wall element and the opening 7 30 is effectively sealed, so that air can flow into the room or other enclosure with which the device is associated only through said casing A.

Within the casing section 1 are spiders or other suitable supports designated as 10, and 35 mounted on said supports and disposed axially of the casing is a small electric motor designated as 11. This motor is of the type comprising a stationary shaft (armature) and a rotatable shell or housing (magnetic field) and, in accordance 40 with the invention, said shell or housing has mounted thereon fan blades 12, whereby, when the motor is in operation, there is produced an inward flow of air through the casing.

Mounted in any suitable manner at the inner 45 end of the casing A is an air distributing device, designated generally as 13, which may be of any suitable type but which preferably is of the type comprising a series of successively larger, truncated, outwardly flaring hollow members disposed 50 in spaced apart relationship to provide a series of outwardly flaring air passageways therebetween, whereby air flowing therethrough is distributed substantially draftlessly. For mounting this air distributing device on the casing A the 55

larger or outermost flaring member of said device may be provided with a sleeve or tubular portion 14 which may be telescoped over the inner end of the section 1 of said casing.

- 5   Mounted in any suitable manner at any suitable point within the casing A and extending thereacross is an air filter of any suitable type designated generally as 15, whereby air flowing through the casing is cleaned before being distributed through the device 13. As illustrated in the present instance, said filter is mounted between the inner end of the casing section 1 and an internal shoulder 16 on the portion 14 of the device 13.
- 10   15   For regulating the amount of air which may pass through the casing A when the motor and fan are operating at any given speed, there is provided a hood element 17 of preferably concavo-convex form for cooperation with the outer end of the outer casing section 2. This hood element, which has its concave side facing inwardly or toward the casing A, is of somewhat greater diameter than the outer end of the casing section 2 and is mounted on a rod 18 which ex-
25 tends centrally therefrom inwardly through the hollow shaft of the motor 11 and the filter 15 and through the air distributor 13 to the inner side of the latter where it is provided with a knob or handle 19 for use in sliding the same inwardly
30 and outwardly. In this connection and as is apparent, by shifting said rod inwardly or outwardly the area of the space between the hood element 17 and the outer end of the casing section 2 through which air may enter the casing A may be varied, thus to regulate the volume of air flowing through the casing for any given motor and fan speed. Moreover, and as will also be apparent, the hood 17 may be adjusted inwardly until it contacts with the outer edge of the casing
35 section 2 and thereby completely prevents any flow of outside air into the room or other enclosure through the casing A. Furthermore, and as is additionally apparent, the hood member 17, because of its concavo-convex form, whereby it overlies the outer end portion of the casing section 2, serves effectively to prevent the entrance of rain into the casing A.

40   Preferably, suitable friction means is provided to hold the hood 17 in different adjusted positions, said means comprising in the present instance a series of annular grooves 20 formed in the rod 18 at points spaced longitudinally therealong, and a ball 21 mounted in a suitable support 22 and urged by a spring 23 against said rod, whereby, depending upon the manual longitudinal displacement of said rod, said ball snaps into one or another of said grooves and thereby holds said rod against accidental longitudinal displacement.

45   Referring now particularly to Fig. 3 of the drawings, it will be observed that the general construction and combination of elements shown therein is the same as illustrated in Figs. 1 and 2 of the drawings. However, as distinguished from the Figs. 1 and 2 embodiment of the invention, the Fig. 3 embodiment employs a motor of the usual type comprising a stationary outer shell or housing (magnetic field) containing a rotatable shaft (armature), on which, preferably at the inner end of the motor, is mounted a cylindrical element 24 which preferably is of no greater diameter than the motor housing and which carries the fan blades designated at 12^a. In other words, Fig. 3 illustrates, as distinguished from the construction shown in Figs. 1 and 2, that a motor of

5   the rotatable shaft, stationary housing type may readily be used in lieu of a motor of the stationary shaft, rotatable housing type. Fig. 3 also illustrates that the outer end portion of the motor housing may be of rounded or streamline shape to guide the inflowing air around the motor.

10   Referring now particularly to Fig. 4 of the drawings, it will be observed that again the general construction and combination of elements shown there is the same as illustrated in Figs. 1 to 3 of the drawings, but that, as distinguished from the Figs. 1 to 3 constructions, the inner casing section is comprised by the tubular portion 14^b of the air distributing device designated generally as 13^b, and that the filter element 15^b is disposed at the outer end of the casing instead of between the fan and the air distributor. Fig. 4 further illustrates that the motor is of the type illustrated in Fig. 3 and that the fan blade carrying cylindrical element 24^b may have an inwardly directed streamlined end 24^c to guide the inflowing air to the passageways of the air distributing device.

15   While a fan of any suitable type may be employed in the present device, the fan preferably employed is of the highly efficient type shown whereby the present device, considered in its entirety, may be of relatively small size for any given installation. As shown in Figs. 1 to 4 the present fan comprises a cylindrical hub, comprised in the case of the Figs. 1 and 2 embodiment of the invention by a motor shell and in the case of the Figs. 3 and 4 embodiments of the invention by a member entirely separate from the motor and formed to be mounted either on a 30 motor shaft or any other driven shaft. In any event, the blades of said fan preferably are formed in pairs, designated as 25, 25^a from suitable material in the form of elongated strips by bending said strips intermediately upon themselves along lines at right angles thereto into approximately V-shape. Alternatively, said pairs of blades may be molded from suitable material or they may be formed in any other desired manner. In any event, they are fastened in any suitable manner at their free ends to the hub with their free ends spaced both circumferentially around and longitudinally along the hub, which, of course, results in their planes being disposed diagonally with respect to a radial plane including the axis of the hub and passing through the blades. In addition, the diagonal disposition of the blades and the relative disposition of successive blades preferably is such, or approximately such that the inner or free ends of the blades 25 40 at one end of the hub are aligned with the inner or free ends of the next succeeding blades 25^a at the other end of the hub. Because of this dual 45 fan blade arrangement in which the blades at the receiving end of the fan slope outwardly toward the blades at the delivery end of the fan and the latter blades slope outwardly toward the blades at the receiving end of the fan, and in which the spaces between the respective pairs of blades are closed at their outer ends, rotation of 50 the fan results in air first being acted upon by the blades at the receiving end of the fan and having an initial impulse imparted thereto, and then being acted upon by the blades at the delivery end of the fan and having a final impulse 55 imparted thereto, while being restrained against outward flow by the closed outer ends of the spaces between the respective pairs of blades, with the final result that for a fan having any given number of blades of any given length and 60

width rotating at any given speed, the propulsion effect is exceptionally high. Accordingly, in order to obtain a given propulsion effect the blades of the present fan may be relatively short. Therefore, by the use of fans of the present type in devices of the present type, such devices may be of relatively small size for any given installation.

According to the alternative fan construction shown in Fig. 5, the arrangement is the same as shown in Figs. 1 to 4 except that a second set of pairs of blades 25^b, duplicating a first set substantially as shown in Figs. 1 to 4, is provided and the blades of this second set are alternated with corresponding blades of the first set circumferentially of the fan, the innermost blades of each set being disposed midway between the blades of the other set longitudinally of the fan. In this case the operation is the same as in the case of the fan shown in Figs. 1 to 4, but due to the second set of pairs of blades the propulsion effect of the fan is correspondingly increased.

From the foregoing description considered in connection with the accompanying drawings it is believed that the features and advantages of the invention will be clearly understood. It is desired to point out, however, that while only certain specific embodiments of the invention have been illustrated and described, the same is readily capable of embodiment in specifically different mechanical embodiments within the spirit and scope of the invention as defined in the appended claims.

We claim:

1. An air supply device of the character described comprising a hollow casing open at its ends, means for mounting said casing in a wall opening, an air-distributing device comprising a plurality of mutually spaced hollow flaring members at the inner end of said casing, a fan within said casing for producing a flow of air therethrough, a hood at the air inlet end of said casing to be adjusted toward and from said end to regulate flow of air through the casing, and means extending from said hood through the

casing, and said air-distributing device to the inner end of said casing for adjusting said hood.

2. An air supply device of the character described comprising a hollow casing open at its ends, means for mounting said casing in a wall opening, a motor within said casing having a hollow shaft, a fan within said casing driven by said motor for producing a flow of air through the casing, a hood at the inlet end of said casing to be adjusted toward and from said end to regulate flow of air through the casing, and a rod extending from said hood through said motor shaft to the inner end of the casing for adjusting said hood.

3. An air supply device as set forth in claim 2, including friction means cooperating with the rod to hold the latter and the hood in different adjusted positions.

4. An air supply device of the character described comprising a hollow casing open at its ends, means for mounting said casing in a wall opening, a motor within said casing having a hollow shaft, a fan within said casing driven by said motor for producing a flow of air through the casing, an air distributing device at the air outlet end of said casing, a hood at the inlet end of said casing to be adjusted toward and from said end to regulate flow of air through the casing, and a rod extending from said hood through said motor shaft and said air distributing device to the inner end of the latter for adjusting said hood.

5. An air supply device of the character described comprising a hollow casing open at its ends, means for mounting said casing in a wall opening, means for producing a flow of air through said casing, an air distributing device comprising a plurality of mutually spaced hollow flaring members and detachably connected with the inner end portion of said casing, and an air filtering element held between the casing and said air distributing device being mounted in the neck-portion of said air-distributing device.

FRANZ J. KURTH.

FRIEDRICH HONERKAMP. 45
